UNITED STATES PATENT OFFICE.

HARRY M. FRIDLEY, OF BROOKLYN, NEW YORK.

GAME.

Application filed November 7, 1923. Serial No. 673,310.

To all whom it may concern:

Be it known that I, HARRY M. FRIDLEY, citizen of the United States, residing at Brooklyn, in the county of Kings and State 5 of New York, have invented certain new and useful Improvements in Games, of which the following is a specification.

This invention relates to the art of games and toys, and has particular reference to an 10 improved form of game apparatus.

The object of the invention is to provide a simple and cheap form of game that will serve to provide a great amusement for both young and old, and that may be played both 15 indoors and out of doors.

Other objects will appear as the nature of the invention is better understood and the same consists in the novel form, combination and arrangement of parts hereinafter 20 more fully described, shown in the accompanying drawings and claimed.

In the drawings, wherein like reference characters indicate corresponding parts throughout the several views:

25 Figure 1 is a front elevational view of the game board in a set up or operative position.

Figure 2 is an end elevational view thereof.

30 Figure 3 is a perspective view of one of the bats or paddles employed.

Figure 4 is an elevational view of one of the balls.

Figure 5 is a perspective view of one of 35 the counters, and

Figure 6 is a perspective view of one of the cards employed for determining the order of play and designating color of the respective player.

40 Referring more in detail to the drawing, the invention embodies a board structure of easel-like form including an elongated substantially rectangular board member 5 that is adapted to be supported in a substantially

45 upright position upon one of its longer edges by means of braces or legs 6 when the latter are disposed at an inclination as shown at Figure 2, said braces or legs 6 being of any desired or preferred number, and flexibly 50 connected as at 7 at their upper ends to the upper portion of the back of the board 5.

A plurality of longitudinal series of openings is provided by forming similar notches 8 in the lower ends of the board 5 from end 55 to end thereof, said notches being uniformly spaced and of greater width than

the spaces between the adjacent points of the same.

Printed or otherwise provided above each opening upon the front face of the board 5 is a colored area as indicated generally at 9, the colored area of each notch or opening being different from the color above each of the remaining notches or openings and being provided with a numeral of value as indicated generally at 10. The valued numerals as at 10 are preferably of different values and progress from the central notch or opening to the sides of the boss as shown.

Also printed upon the front surface of the bolt 5 above each of the openings 8 are colored areas 11, each of which correspond in color to the color of the area 9 therebelow.

The game further embodies a plurality of 75 bats corresponding in number to the number of openings or notches 8 and each bearing the color of one of the colored areas above their openings. As these bats or paddles are of similar form, only one of the same has been shown and as indicated in Figure 3, each of the same includes a strip of board formed with a circular or disc portion 12 at one end and having its remaining portions relatively narrow to provide a 80 handle 13. The game further includes a plurality of balls as indicated at 14 in Figure 4, which balls are of sufficiently small diameter to pass through the notches 8, but not too easily due to the fact that the diameters of the balls are nearly as great as the width of the notches. Each ball has a colored area thereon as indicated at 15 corresponding to one of the colored areas 9 of the board 5.

95 The invention further consists in the provision of a plurality of counting cards as indicated at 16 having numerals on the faces thereof as indicated at 17, which numerals progress on the respective cards from five 100 to ninety. Only one of these cards is shown as the only difference between the same is the value of the number 17 marked thereon, and each card is provided with a return bent tongue as indicated at 18 whereby the cards 105 may be suspended or clipped over the upper edge of the boss 5 co-incident with a desired one of the colored areas 11.

A plurality of further cards 19 are provided, the number of these cards depending 110 upon the number of notches provided at 8 in the boss 5, and these cards are numbered

as generally indicated at 20 successively from 1 up. The cards 19 further have colored areas as generally indicated at 21, the colored area of each card corresponding to 5 the color of the area above one of the notches or openings 8 as indicated at 9 on the surface of the board 5. Attached to the board 5 is a relatively long string 22, the purpose of which will presently become apparent.

In use, the board is set up in a substantially vertical position as shown in Figures 1 and 2, and the line 22 is extended from the front of the board 5, so that a mark 15 may be made upon the ground or other surface at the extreme end of said cord 22 to facilitate the marking of a base line parallel with the plane of the board. This base line is where each player will place his ball 20 before batting it toward the board, and each player will then draw a colored card 19 to determine the order of playing. The players then collect the bat and ball corresponding to the colors shown.

25 For instance, the player drawing "red" will place his ball on the base line and try to bat it through one of the openings in the board 5. Each player has three strokes which is called an inning, and the scorer 30 returns the ball after each stroke. This procedure continues until each player has had an inning after which the player who drew "red" starts the second inning and this is continued as above until one of the 35 players scores a game.

The game may be played by a swinging stroke or a push stroke of the bat, but the stroke to be used should always be decided upon before beginning the game. The 40 game may be played by two or more players, by partners or by sides of three.

In playing the game, the total count preferably should consist of exactly ninety points. As each player bats a ball through 45 an opening, the scorer returns the ball and scores at the top of the board on the color of the player batting the ball the number shown above the opening into which the ball has been batted, that is, if the player is red 50 and the first ball batted enters the opening 15, a corresponding number is placed on red at the top of the board through the use of the cards 16. If the second ball batted enters opening 20, the number 15 is removed 55 and the number 35 placed on red. On the other hand if the third ball batted enters opening 5, the number 35 is removed and number 40 is placed on red. This score remains until the next inning and 60 continued in like manner for each inning until he or some other player scores a game or until he is out.

When a player scores a game (90 points) all scores are removed, a new drawing for

the order of play being then made, and a 65 new game started.

If any player makes more than 90 points he is out and forfeits all points scored and his uncompleted inning and starts over again when his next turn comes around. 70

A player batting the ball through an opening of the same color he is using counts double. That is, if red bats his ball through the opening above which is a red area, he counts 20 instead of 10. No score is counted 75 for balls that do not go through an opening.

From the above description, it is believed that the construction and manner of use as well as the interesting nature of the present invention will be readily understood and appreciated by those skilled in the art. 80

What I claim as new is:

1. In a game of the character described, an easel like structure including a board with means for supporting the same upon one edge in a substantially upright position, said board having a plurality of notches in the lower edge thereof through which balls may be projected, a flexible member or string attached to the board for use in determining the distance of a base line from the front surface of a board, said board having a colored area above the notches thereof with the colored area of each notch differing from that of the remaining notches, a value numeral associated with each colored area above each notch, and a plurality of cards corresponding in number to the number of notches and each having a color area and a numeral upon one face thereof for designating the order of play, each card having its colored area corresponding to the colored area above one of said notches in the board. 90 95 100

2. In a game of the character described, an easel like structure including a board with means for supporting the same upon one edge in a substantially upright position, said board having a plurality of notches in the lower edge thereof through which balls may be projected, a flexible member or string attached to the board for use in determining the distance of a base line from the front surface of a board, said board having a colored area above the notches thereof with the colored area of each notch differing from that of the remaining notches, and a value numeral associated with each colored area above each notch, said board having a certain colored area thereon above each first named colored area and similar to the latter, and scoring cards having means for suspending the same from the upper edge of the board over said second named colored area. 110 115 120 125

In testimony whereof I affix my signature.
HARRY M. FRIDLEY.
